(57) **CLAIM**

We claim the ornamental design for a battery for electronic equipment, as shown and described.

DESCRIPTION

FIG. 1 is a rear perspective view of a battery for electronic equipment, showing our new design;
FIG. 2 is a front perspective view thereof;
FIG. 3 is a front elevational view thereof;
FIG. 4 is a rear elevational view thereof;
FIG. 5 is a right-side elevational view thereof;
FIG. 6 is a left-side elevational view thereof;
FIG. 7 is a top plan view thereof; and,
FIG. 8 is a bottom plan view thereof.
